UNITED STATES PATENT OFFICE.

ADAM DANNER, OF YONKERS, NEW YORK.

BARREL-SCRUBBING MACHINE.

957,659.

Specification of Letters Patent. Patented May 10, 1910.

Application filed May 6, 1909. Serial No. 494,443.

To all whom it may concern:

Be it known that I, ADAM DANNER, a citizen of the United States of America, residing at Sherwood Park, Yonkers, county of 5 Westchester, and State of New York, have invented certain new and useful Improvements in Barrel-Scrubbing Machines, of which the following is a specification.

This invention relates to improvements in 10 barrel-scrubbing machines by which the scrubbing brush for the exterior belly-shaped portions of the barrels and the brushes for cleaning the heads of the barrels can be adjusted with great facility to 15 any size of barrels required to be cleaned after they are delivered from the barrel-soaking machine, the parts for adjusting the brushes being easily accessible from the side or end of the scrubbing machine.

20 The invention consists of certain details of construction relating to the adjusting mechanisms of the segmental brush and of the horizontal head-brushes, as will be fully described hereinafter and finally pointed out 25 in the claims.

In the accompanying drawings, Figure 1 represents a rear-elevation of my improved machine for scrubbing barrels, Fig. 2 is a side-elevation, Fig. 3 is a detail vertical 30 transverse section on line 3, 3, Fig. 2, of a portion of the adjusting mechanism for the segmental brush, and Fig. 4 is a detail vertical transverse section on line 4, 4, Fig. 2, showing the adjusting mechanism for the 35 head-brushes of the machine.

Similar letters of reference indicate corresponding parts throughout the several figures of the drawings.

Referring to the drawings, *f* represents 40 the supporting frame of the improved barrel-scrubbing machine. The frame *f* is composed of two upright side-standards *f*¹ which are connected rigidly by transverse brace- 45 rods *f*² and provided at their upper horizontal portion with journal-bearings for the shafts *r*¹ of two rubber-covered rollers *r* on which the barrels to be scrubbed are placed. On the shafts of the rollers *r* are arranged 50 pulleys *r*² which are driven by a belt *r*³, said rollers receiving the barrels and rotating them after they are delivered thereto by an intermediate connection from a barrel-soaking machine in which the exterior and interior of the barrels are prepared for cleaning. 55 The supporting standards *f*¹ are provided at the outgoing-end for the barrels

with inclined bracket-arms *f*³, to the outer forked ends of which are pivoted two forwardly-inclined supporting arms *a*, the upper ends of which are connected by a transverse arched brace *a*¹. To the center of the arched brace *a*¹ is applied a holder *a*⁴ by a suitable clamping mechanism *a*². The back *a*³ of a segmental scrubbing brush *B*, by which the exterior surface of the barrel is 60 scrubbed, is clamped to the holder *a*⁴. The segmental scrubbing brush *B* extends almost entirely across the distance between the upright side-standards *f*¹ so as to permit the washing of the circumference of larger and 65 smaller barrels as they are transferred to the rotary driving rollers. Adjacent to the arched supporting brace *a*¹ and parallel therewith is arranged an arched perforated tube *p*¹ which is connected at its middle portion with a water-supply pipe *p* and hose *p*² by which the water is conducted into the tube *p*¹ and through the perforations of the same on the scrubbing brush *B* so as to be delivered into the space between the rows of 70 75 bristles of the same and then conducted onto the outer circumference of the barrel.

On the inclined brush-supporting rods *a* are arranged stops *d* which are tightly attached by clamping means *d*¹ to the supporting rods. The stops *d* abut against anti-friction rollers *d*² at the upper ends of vertical pillars *d*³ which are pivoted at their lower ends to slide-blocks *d*⁴ which are guided in inclined slots *d*⁵ arranged in the 80 inclined bracket-arms *f*³, the slide-blocks *d*⁴ being connected with inclined rack-bars *d*⁶ which are guided along fixed blocks *d*⁸ on the inside of the side-standards *f*¹ and held in mesh with pinions *d*⁷ on a transverse shaft 85 *d*⁹ that is provided with hand-wheels *d*⁹ at each end, outside of the side-standards *f*¹, so as to permit the adjustment of the pillars *d*³ to a higher or lower position, and thereby the raising or lowering of the inclined arms 90 *a* on their pivot-connection with the upper ends of the bracket-arms *f*³. To the middle portions of the upright pillars *d*³ are attached horizontal arms *e*, which carry counterbalancing weights *w* near their outer ends, 95 the weights being capable of adjustment on said arms for the purpose of counterbalancing the weight of the segmental scrubbing brush *B* and its supporting arms and braces for permitting the easy adjustment of the 100 brush *B* relatively to the circumference of the barrel to be scrubbed. By a ratchet-

wheel d^{10} on the shaft d^8 and a check-pawl d^{11} the rack-bars and the parts connected therewith are rigidly held in the position to which they are adjusted. By the adjustment 5 of the inclined arms a the scrubbing brush B can be readily adjusted to the circumference of smaller or larger barrels radially to the axis of the same, so that the brush is always placed in the most advantageous position 10 for the proper scrubbing of the circumference of the barrel, the adjustment being accomplished readily from either side of the machine by means of the hand-wheels d^9 , so as to obviate the necessity of passing around 15 from one side of the machine to the other for adjusting the scrubbing brush B into proper position relatively to the barrels. The lower ends of the inclined head-supporting arms a are provided with projections a^3 which serve as stops for the arms a when the same are swung on their pivots in backwardly-inclined position, so as to give convenient access to the scrubbing brush B and its supporting and water-supplying 20 parts for the convenient inspection, cleaning and repairing of the same.

A scrubbing brush C for cleaning the heads of the barrel is arranged on each side-standard f^1 of the machine, the back of each 30 scrubbing brush C being rigidly clamped to a U-shaped holder g which is provided with a horizontal shank g^1 having a handle g^2 at the outer end. The shank g^1 is slotted and supported on a guide-block g^3 at the upper 35 end of an inclined arm g^4 which is loosely pivoted at its lower end to an inclined slide-block g^5 . The slotted shank g^1 of the scrubbing brush C is rigidly clamped by a thumb-screw g^6 and screw-post g^7 to the guide-piece g^3 at the upper end of the inclined arm g^4 , as shown in Fig. 4. The slide-block g^5 for the pivoted lower end of the inclined arm g^4 is guided in ways of an outwardly-inclined arm g^{10} and clamped by a screw-post g^9 , plate g^8 and thumb screw-nut g^8 rigidly to the same. The bracket-arm g^{10} is attached by its lower end by means of fastening screw-bolts g^{11} to the side-standard f^1 , as shown clearly in Figs. 2 and 4. The slide-blocks g^5 are adjusted higher or lower in the inclined bracket-arms g^{10} so that the head-scrubbing brushes C may be adjusted higher or lower, and in connection with the 45 pivoted inclined arms g^4 and slotted shanks g^1 of the holders g , and clamping-nuts g^6 , inwardly toward the heads of the barrel, so that the scrubbing brushes C can be adjusted exactly to center of the heads of a larger or smaller barrel and readjusted after the 50 brushes C are worn off, as required. The head-scrubbing brushes C are made of sufficient length so as to clean the heads of the largest barrels to be scrubbed. The adjustment of the head-scrubbing brushes is readily 55 accomplished by taking hold of the handle 60

of the shank g^1 with the left hand, loosening the clamping thumb-nut of the shank with the right hand, and then shifting the head of the brush forward so that the bristles contact with the head of the barrel to be 70 cleaned. When the scrubbing brushes C are to be adjusted higher or lower to the center of the barrel, the slide-block g^5 is moved on the guideways of the bracket-arms g^{10} by loosening the clamping thumb-nut g^8 on the 75 inclined bracket-arm g^{10} until the brush is placed in position diametrically across the center of the head of the barrel to be scrubbed. The parts are then clamped tightly again by the clamping-nuts g^8 , g^6 , 80 the scrubbing brush being then in position for the proper scrubbing action on the barrel. The action of gravity tends to move the inclined arms g^4 and the brush c to hold the bristles of the brush c against the barrel. 85 When the upper segmental brush and the head-scrubbing brushes are properly adjusted, the machine is started, the barrel rotated by the rollers and then scrubbed simultaneously on the circumference and the heads by 90 the different scrubbing brushes.

Having thus described my invention, I claim as new and desire to secure by Letters Patent:

1. In a barrel-scrubbing machine, the combination, with the supporting standards, of 95 rotary barrel-supporting rollers, a segmental brush above the barrel for scrubbing the outer surface of the same, freely movable inclined arms pivoted to the standards and 100 having a transverse brace-rod for supporting the segmental scrubbing brush, counterbalanced means engaging said arms for partially supporting the arms, and means carried by said arms for engaging said counterbalanced means and limiting the downward movement of said inclined arms. 105

2. In a barrel-scrubbing machine, the combination, with the supporting standards, of 110 rotary barrel-supporting rollers, a segmental brush for scrubbing the circumference of the barrel, inclined brush-supporting arms pivoted to said standards, stops on said arms, 115 pivotally mounted upright pillars abutting against said stops, means for raising or lowering said pillars and inclined supporting arms, and counterbalancing weights connected with said pillars.

3. In a barrel-scrubbing machine, the combination of supporting side-standards having 120 inclined bracket-arms, rotary barrel-supporting rollers turning in bearings of said standards, inclined arms pivoted to the outer ends of the bracket-arms, an arched brace connecting the upper ends of said inclined arms, a segmental scrubbing brush supported on said arched brace, adjustable stops on the inclined arms, pivotally mounted upright pillars abutting at their upper 125 ends against said stops, means for adjusting 130

the pillars into a higher or lower position, and weights connected with the upright pillars for counterbalancing the weight of the segmental brush and its supporting mechanism.

4. In a barrel-scrubbing machine, the combination, with the side-standards, of outwardly-inclined bracket-arms attached to said side-standards and provided with guide-ways, slide-blocks guided in said ways, means for clamping said slide-blocks to the inclined bracket-arms, inwardly-inclined arms pivoted to said slide-blocks, scrubbing brushes for the heads of the barrel, and means for adjusting said brushes forward and backward on the upper ends of the inwardly-inclined pivot-arms for adjusting the head-brushes higher or lower and inwardly and outwardly relatively to the heads of the barrels.

5. In a barrel-scrubbing machine, the combination of side-standards, outwardly-inclined bracket-arms attached to the side-standards and having inclined ways, adjustable slide-blocks guided in the ways of said bracket-arms, inwardly-inclined arms pivoted to said slide-blocks and provided with guide-blocks at their upper ends, brush-holders provided with slotted shanks guided on guide-blocks of the pivot-arms, means for clamping the slotted shanks to the guide-blocks, and means for clamping the heads of the brushes to the holders.

In testimony, that I claim the foregoing as my invention, I have signed my name in presence of two subscribing witnesses.

ADAM DANNER.
